Primary Examiner — Samantha Wood(74) *Attorney, Agent, or Firm* — Carmody Torrance Sandak & Hennessey LLP(57) **CLAIM**

The ornamental design for a wristwatch with strap, as shown and described.

DESCRIPTION

FIG. 1 is a perspective view of a wristwatch with strap showing my new design;

FIG. 2 is a front elevation view of thereof;

FIG. 3 is a back elevation view of thereof;

FIG. 4 is a right side elevation view of thereof;

FIG. 5 is a left side elevation view thereof;

FIG. 6 is a top plan view thereof; and,

FIG. 7 is a bottom plan view of thereof.

The broken lines are included for the purpose of illustrating portions of the article and form no part of the claimed design.
